LAMP

John W. Daehler, Los Angeles, Calif.

Original application July 17, 1934, Serial No. 735,623. Divided and this application July 2, 1936, Serial No. 88,500. Renewed January 30, 1939

5 Claims. (Cl. 240—7.1)

This invention relates to lamps, and more particularly to lamps adapted to withstand shocks, jars and the vibration incidental to or attending upon their use upon vehicles, moving machinery and the like, and in fact in any position where a lamp is apt to be subjected to such usage as would tend to extinguish the light furnished thereby or otherwise injure the lamp or parts thereof.

10 This application is a division of my co-pending application Serial No. 735,623, filed July 17, 1934, for Lamps.

A particular field of usefulness for the lamp is in the automotive field, where the shocks and vibrations incident to the travel of a motor vehicle over rough roads or due to collisions and contacts with other vehicles cause the rapid destruction of the filament in the electric globes ordinarily depended upon for the illumination 15 of the roadway and as danger signals to be observed by the drivers of other vehicles and the public generally. Inasmuch as the extinguishment of the tail light or other warning lights, not directly visible to the driver of a motor vehicle 20 equipped with the same, frequently results in serious accidents, it is one of the principal objects of the present invention to provide a safety lamp for use in such positions in which the delicate filament, as well as all other lamp portions are, as far as possible, insured against 25 damage or destruction.

A further object of the invention is to provide a lamp adapted for use in the gun turrets of water craft, and like places and positions, and 30 which may be subjected, without damage, to the violet shocks occasioned by the firing of heavy artillery or ordinance of any kind whatsoever.

With the above and other objects in view, including the provision of a lamp in which the globe or filament carrying element is cushioned or yieldably mounted within a casing as well as being readily removable from such casing for purposes of replacement or substitution without the use of any tools whatsoever, the invention 35 consists in general of certain combinations of parts hereinafter fully described, shown in the drawing and particularly claimed.

In the drawing:

Figure 1 is a vertical side elevation showing a 40 vehicle lamp such as a tail light, constructed and organized to embody the invention;

Figure 2 is a central vertical sectional detail view of the tail light shown in Figure 1;

Figure 3 is a face view of the tail light shown 45 in the other figures;

Figure 4 is a horizontal sectional detail view showing how the tail light body may be flexed or temporarily distorted for purposes of lamp globe replacement as well as for purposes of receiving and withstanding shocks and impacts without damage or failure in its functioning.

The parts in the several figures are designated by reference characters.

Referring with particularity to the drawing, in the embodiment of the invention therein shown, A designates a lamp casing or body formed of resilient, yielding and cushioning material, such as rubber of the proper flexibility and hardness to permit distortion under the pressure of severe impacts or by pulling at the casing mouth 15 with the fingers and thumb to permit the removal of an axially projected and extended lens, B; C designates an electric light globe or illuminating means, D designates yielding and cushioning supporting means for the removable electric globe 20 C, E designates electrical energy supplying means, and F designates means for supporting the casing A and its associated and combined features from a vehicle frame member, body or other place of attachment, the supporting means F being shown 25 as adapted for ready connection with or disconnection from both the casing or body A or the vehicle member indicated at G.

The casing A is shown in this preferred embodiment of the invention as of generally cylindrical form and open at one end, as at a, where the cylindrical peripheral wall 8 is provided with a flexible yielding resilient lens-retaining inwardly directed lip 9 which lies outwardly of an internal annular or circular channel 9' formed for 30 the reception of and to snugly house the flanged rearward peripheral portion 10 of the lens B. The cylindrical outer casing wall 8 is shown as thickened inwardly of the channel 9' and as of uniform thickness throughout the length of the internal lamp-chamber formed at A', the integral resilient rubber body or casing A terminating in a relatively thin integrally-formed cushioning vibration-resisting lamp-supporting or lamp-mounting diaphragm 11; at the channel 9' the 35 thickened wall, shown at 12, forms a seat 12 for the inner flat annular face 13 formed at the lens flange portion 10.

The diaphragm, constituting the end wall of the casing opposite the lens, is centrally apertured 40 at 11' to accommodate the lamp-supporting means D.

This diaphragm 11 is shown of much greater diameter than the globe supporting means D which is mounted thereon, and consequently pre- 45

sents a relatively great area of yielding, resilient rubber in sheet form, held in stretched condition and supported at its edges by the integrally formed thick cylindrical wall 8.

5 The resilient casing A is shown as having a circumferential relatively broad and shallow supporting - means - receiving channel 8a formed therein to accommodate the supporting means F and provide for the ready attachment of the resilient casing A thereto or the release of the same therefrom.

10 The yielding and cushioning and shock-absorbing diaphragm upon which the globe-mounting means D is supported provides against any shocks to the lamp and its filament. Such mounting means D is shown as a metallic lamp-socket 14 which comprises a pair of opposed spaced arm members 15 of accurate cross-sectional form adapted to snugly embrace a lamp-globe base between them, and which arms extend longitudinally of the axis of the casing A from a transverse base plate or disc portion 16 with which they are preferably formed. This base plate lies against the inner face of the resilient diaphragm 11, and a neck 16' extending through the aperture of the diaphragm connects the base plate with an annular flange 16'' at the outer face of the diaphragm. Each globe-embracing arm has a notch 17 formed therein in one of its longitudinal edges, and each notch extends first laterally inward, and then toward the open mouth of the socket 18 as at 17'. These notches are formed at diametrically opposite points in the socket in order that each may receive one of a pair of diametrically opposite pins 19' arranged to extend laterally of the globe-base 19 of the means C, as will be readily understood by those skilled in the art. Slidably mounted between the arm members 15 is a piston-like member or apertured disc 20 formed of insulating material. This disc 20 is normally pressed towards the mouth of the socket by a coil spring 21.

15 The illuminating means C is shown as a small globe of glass 22 having an electrically lighted filament therein and mounted upon the base 19, this lamp being of the conventional type. The base makes contact with the socket arms and the second contact is made by a central base contact point 23 which engages a contact point at 20 the corresponding face of the disc. A circuit wire 24 extends from the socket base to the channel 8a where it contacts with the metallic supporting means F, and through the medium of which it is grounded upon the vehicle frame. The globe may be inserted in the socket in the usual manner.

25 The means E may comprise in addition to the wire 24, a flexible cable 25 which terminates at its one end in the disc contact point 27; the other end of the cable may be connected in circuit in the usual manner.

30 The means F is shown as a one-piece metallic strap 28, which has a circular loop 28' partly surrounding the casing A and which lies in the channel 8a in engagement with the circuit wire 24. Each terminus of the strap is bent outwardly from the loop as at 28'' where the parallel spaced portions are apertured to receive a clamping bolt 29 having a nut 30 for tightening 35 the strap. Beyond the parallel portions each strap end is bent to conform to the vehicle frame and apertured to receive an attachment screw or bolt 30' for securing the same to the frame at G.

35 When a lamp is to be replaced by a fresh one, it is only necessary to work or pull the resilient

flexible material at the lens-retaining lip 9 outwardly, the lip readily yielding under such treatment by the fingers and thumb of one hand, and work the lens out of its socket with the fingers and thumb of the other hand through the open mouth of the casing, the projected and extended lens front being especially adapted and formed to facilitate such removal and furnishing the necessary leverage for a prying action.

40 To adapt the lens for this dual purpose, the outer surface may be in the form of a paraboloid or of approximately semi-ovoidal form, the blunt lens point lying far outwardly of the casing mouth, as at 31, and the inner surface may be formed of a series of conical or like surfaces 32, 15 joined by step formations 33.

45 The lamp globe is so held, in a position lying upon the axis of the casing A and extending away in right angular relation from the central portion of the diaphragm, that oscillations of the same laterally as well as forwardly and backwardly may be caused by jars or vibration incident to vehicle travel, due to temporary distortion of the rubber diaphragm, which usually is placed in a vertical position when the light is upon a road 25 vehicle, while the axis of the lamp is horizontal, without injury to the filament or glass globe, the cushioning action of the supporting parts preventing any damage thereto; nor can the lamp globe ordinarily strike the cylindrical casing wall 30 although such striking would not damage the lamp inasmuch as such wall acts as a cushion also. To remove the lamp casing from the vehicle it is only necessary to loosen the clamping screw and withdraw the casing and combined 35 parts through the loosened loop.

50 It will be understood that many changes and departures may be made from the specific disclosure herein without departing from the spirit of the invention and the terms of the following 40 claims.

55 Having thus disclosed my invention, I claim and desire to secure by Letters Patent:

1. A courtesy lamp including a hollow body of 45 resilient stiff soft rubber, said body being cylindrical in form and having an integral closure diaphragm at one end, the other end being open and having an internal peripheral groove, said diaphragm having a central opening, a lens having a peripheral flange detachably seated in said 50 groove, a lamp socket having a lamp holding portion located in the body, said socket having a reduced portion fitting the opening in the diaphragm and provided with a flange resting against the outer face of the diaphragm, and 55 means supporting the body and adapted to be secured to a vehicle part.

2. A courtesy lamp including a hollow body of 60 resilient stiff soft rubber, said body being cylindrical in form and having an integral closure diaphragm at one end, the other end being open and having an internal peripheral groove, said diaphragm having a central opening, a lens having a peripheral flange detachably seated in said 65 groove, a lamp socket having a lamp holding portion located in the body, said socket having a reduced portion fitting the opening in the diaphragm and provided with a flange resting against the outer face of the diaphragm, said body having an external peripheral groove intermediate its ends, a stiffening and supporting ring seated in the last named groove, and a supporting leg extending from said ring.

3. A courtesy lamp including a hollow body of 70 resilient stiff soft rubber, said body being cylind-

drical in form and having an integral closure diaphragm at one end, the other end being open and having an internal peripheral groove, said diaphragm having a central opening, a lens having a peripheral flange detachably seated in said groove, a lamp socket having a lamp holding portion located in the body, said socket having a reduced portion fitting the opening in the diaphragm and provided with a flange resting against the outer face of the diaphragm, said diaphragm being thinner than the remainder of the body to yield readily under shocks, and means supporting the body and adapted to be secured to a vehicle part.

4. A courtesy lamp including a hollow body of resilient stiff soft rubber, said body being cylindrical in form and having an integral closure diaphragm at one end, the other end being open and having an internal peripheral groove, said diaphragm having a central opening, a lens having a peripheral flange detachably seated in said groove, a lamp socket having a lamp holding portion located in the body, said socket having a reduced portion fitting the opening in the diaphragm and provided with a flange resting against the outer face of the diaphragm, said

diaphragm being thinner than the remainder of the body to yield readily under shocks, said body having an external peripheral groove intermediate its ends, a stiffening and supporting ring seated in the last named groove, and a supporting leg extending from said ring.

5. A clearance or like lamp of the character disclosed including a hollow body of resilient stiff soft rubber, said body being substantially cylindrical in form and having an integral closure diaphragm at one end, the other end being open and having an internal peripheral groove, said diaphragm having a central opening, a lens having a peripheral flange detachably seated in said groove, a lamp socket having a lamp holding portion located in the body, said socket being fitted in said opening and supported by said diaphragm, said diaphragm being thinner than the remainder of the body to yield readily under shocks, said body having an external peripheral groove intermediate its ends, a stiffening and supporting ring seated in the last named groove, and a supporting leg extending from said ring.
